UNITED STATES PATENT OFFICE.

VITUS SCHWANINGER, OF OGGERSHEIM, NEAR MANNHEIM, GERMANY.

APPARATUS FOR RAISING LIQUIDS.

No. 923,587.

Specification of Letters Patent.

Patented June 1, 1909.

Application filed November 27, 1908. Serial No. 464,745.

To all whom it may concern:

Be it known that I, VITUS SCHWANINGER, a subject of the German Emperor, and residing at Oggersheim, near Mannheim, Germany, have invented certain new and useful Improvements in Apparatus for Raising Liquids, of which the following is a specification.

The present invention relates to apparatus for raising liquids and an important object is to provide improved apparatus for elevating liquids by means of steam or other gaseous fluid under pressure admitted by means of an electrically controlled admission valve.

In the present invention the electric circuit by means of which the valve-controlling electromagnet or solenoid is energized for opening the valve is closed by the arrival of the level of the liquid at an upper contact, and remains closed until the level of the liquid has fallen through a predetermined distance.

One construction embodying the invention is shown by way of example in the accompanying drawing, in which—

Figure 1 is a vertical elevation of the apparatus, partly in section, and Fig. 2 is a like view of a detail on a larger scale.

Referring to the drawing, 1 is the pressure chamber, and 2 the delivery pipe. The latter is electrically conductive and extends into the chamber, as clearly shown, but is electrically insulated from the walls of the chamber. The valve 3 enables the delivery pipe to be placed in communication with the supply pipe 4.

5 is the inlet-pipe for the fluid under pressure; this pipe can be placed in communication with the pressure pipe 6 by means of the valve 7.

8 is the discharge valve for the expanded fluid, and when open enables the latter to pass through the orifice 9 into the atmosphere.

The rod 10 connects the valve 7 with the weighted double-armed lever 11, pivoted at 30, the tendency of the lever being to thrust the valve against its seat. The spring 14, which is comparatively weak, and abuts against the collar 12 on the rod 13 of the valve 8, tends to hold the latter open.

The upper contact hereinbefore referred to is marked 15, and is connected by the wire 16 with the electromagnet 17, the wire 16 being insulated from the pipe 5 at 34. The electromagnet 17 is connected by the wire 33 with the battery or other source of current

18, which is connected by the wire 19 to the pipe 2.

20 is a wire extending to within a short distance of the bottom of the pressure chamber and passing out of the latter through the insulated stuffing box 32 to the metallic sleeve 40 by means of which it is connected to the wire 21. The wires 20 and 21 are connected to this sleeve by means of set-screws 40^a, 40^b, so that the distance of the wire 20 from the bottom of the pressure chamber can be adjusted. The union 22, in which the upper end of the wire 21 is slidable, is connected to the contact-stud 23, as clearly shown in Fig. 2, and this stud is carried by but insulated from the lever 25 which is pivoted at 26. The contact-stud 23 is located below the contact 24 connected to the wire 16. The armature 27 of the electromagnet 17 is connected by the rod 28 to the levers 11 and 25, at 29 and 31 respectively.

The action of the apparatus is as follows:—The inflow of liquid to the pressure chamber takes place through the pipe 4, valve 3, and lower part of the pipe 2. The simultaneous immersion of the wire 20 and pipe 2 into the liquid does not immediately close the electric circuit, since the latter remains open at 23, 24, but when the liquid level reaches the contact 15 the following circuit is closed:—battery 18, wire 33, electromagnet 17, conductor 16, contact 15, liquid in vessel 1, pipe 2, conductor 19. The armature 27 is, therefore, attracted, opens the valve 7 and lifts the contact-stud 23 against the contact 24. The fluid under pressure entering the pipe 5 closes the valve 8 and forces liquid from the pressure chamber through the delivery pipe 2. When the level of the liquid falls away from the contact 15 the electromagnet remains temporarily energized owing to the following circuit being closed, viz.—battery 18, wire 33, electromagnet 17, conductor 16, contacts 24, 23, wire 21, sleeve 40, wire 20, liquid in chamber 1, pipe 2, wire 19. This circuit is broken when the level of the liquid falls away from the wire 20, whereupon the electromagnet 17 which is no longer energized releases its armature and thus allows the weighted lever 11 to close the valve 7. The gaseous fluid in the pipe 5 and pressure chamber continues to act on the liquid by expansion, until the spring 14 is able to re-open the valve 8, or until the level of the liquid in the pressure chamber has fallen below the lower orifice of the pipe 2. The duration of the

period of expansion can be regulated by regulating the distance of the wire 20 from the bottom of the pressure chamber.

It is to be understood that a solenoid may 5 be used instead of an electromagnet without departing from the spirit and scope of the invention.

What I claim as my invention and desire to secure by Letters Patent is:

- 10 1. In apparatus for raising liquids, the combination with a pressure chamber, an inlet fluid-pressure pipe connected therewith, and an admission valve in said pipe, of a supply pipe opening into the lower part of 15 said chamber, an upper contact in the latter, an electrical circuit, adapted to be closed by liquid in said chamber, containing means for opening said valve and connecting said contact with said supply pipe, a lower contact in 20 said pressure chamber, circuit connections connected with the latter contact, and means for connecting the latter circuit connections with the former circuit when the former circuit is closed and said valve is opened.
- 25 2. In apparatus for raising liquids, the combination with a pressure chamber, an inlet fluid-pressure pipe connected therewith, and an admission valve in said pipe, of an insulated supply pipe opening into the lower 30 part of said chamber, an upper contact in the latter, an electrical circuit, adapted to be closed by liquid in said chamber, containing means for opening said valve and connecting said contact with said supply pipe, a vertically 35 adjustable lower contact in said pressure chamber, circuit connections connected with the latter contact, and means for connecting the latter circuit connections with the former circuit when the former circuit is 40 closed and said valve is opened.
- 45 3. In apparatus for raising liquids, the combination with a pressure chamber, of a supply pipe opening into the lower part of the same, an inlet fluid-pressure pipe connected with said chamber, a valve in the latter pipe, a source of current, an electromagnet, a lever carrying the armature of the electromagnet normally closing and controlling said valve, a contact in the upper part of 50 said pressure chamber, conductors connecting in circuit the supply pipe, source of current, electromagnet and said contact, a sec-

ond contact in the lower part of said chamber, a sliding contact connected adjustably with the latter contact, and a lever, connected positively with said armature and carrying said sliding contact, the latter being adapted to contact with one of said conductors when said armature is attracted by said electromagnet.

4. In apparatus for raising liquids, the combination, with a pressure chamber, of an admission fluid-pressure pipe connected therewith a valve in said pipe, electrical valve-controlling means, a contact in the upper part of said chamber, two contacts in the lower part of said chamber, circuit connections, substantially as shown, whereby a valve-controlling circuit containing said means is closed when liquid electrically connects said upper contact with one of said lower contacts, and contact mechanism actuated by said circuit to make a connection whereby another valve-controlling circuit containing said means is closed while the two lower contacts are electrically connected by liquid.

5. In apparatus for raising liquids, the combination with the pressure chamber and an admission pipe connected therewith, electrical means including a circuit for controlling the liquid, said circuit being provided with a wire passing into but insulated from the chamber, a second wire connected adjustably with the former wire, a sliding contact having a stud connected with the second wire, and a lever mounted on said pipe carrying said stud, substantially as shown.

6. In apparatus for raising liquids, the combination with the pressure chamber and an admission pipe connected therewith, of a valve in said pipe, electrical controlling means including a circuit provided with contact mechanism, a lever carrying said valve, and a second lever connected positively with the former lever for actuating said contact mechanism, substantially as described.

In testimony whereof I affix my signature in the presence of two witnesses.

VITUS SCHWANINGER.
